UNITED STATES PATENT OFFICE.

EMMA J. DREVITS, OF SMOLAN, KANSAS.

COMBINED LAMP-BRACKET AND CANDLESTICK.

1,186,652.

Specification of Letters Patent. Patented June 13, 1916.

Application filed April 23, 1915. Serial No. 23,430.

To all whom it may concern:

Be it known that I, EMMA J. DREVITS, a citizen of the United States, residing at Smolan, in the county of Salina and State 5 of Kansas, have invented certain new and useful Improvements in Combined Lamp-Brackets and Candlesticks; and I do hereby declare the following to be a full, clear, and exact description of the invention, such 10 as will enable others skilled in the art to which it appertains to make and use the same.

This invention relates to combined lamp brackets and candlesticks, and one of the 15 principal objects of the invention is to provide a lamp bracket and candlestick which can be quickly clamped onto a table, a sewing machine, a bed, or other support, and which can be used as a bracket for a lamp 20 or for a candlestick, and which will be provided with a handle so that it can be carried about from place to place.

The foregoing and other objects may be attained by means of the construction illustrated in the accompanying drawing, in 25 which—

Figure 1 is a view in elevation of a combined lamp bracket and candlestick made in accordance with this invention, and Fig. 30 2 is a sectional view taken on the line 2—2 of Fig. 1 and showing a lamp in dotted lines supported in the bracket.

Referring to the drawing, the numeral 1 designates a cup-shaped support or bracket 35 for a lamp, said support having preferably a ring 2 connected to the concave portion 3 by means of supporting members 4. A handle 5 is connected to the bracket at the rear. A socket for a candle is integrally 40 connected with its central portion 3 of the bracket, said candlestick being indicated by the numeral 6 and having a solid bottom 7 and an open top 8, said candlestick being mounted in the center of the concave portion 3 so that grease from the candle will 45 be caught by the concave surface.

An integral curved bracket member 7 is connected to the rear side of the candlestick, and at the free end is provided with an enlargement 8 having a screw threaded bore 50 therein. A clamp screw 9 is mounted in the threaded bore of the enlargement 8, and is provided with a smooth head 10 to bear

against the underside of a table, desk, sewing machine or other support, while the 55 outer end of the screw 9 is provided with a milled head 11.

From the foregoing it will be obvious that the combined lamp bracket and candlestick may be clamped to the edge of a table, desk, 60 sewing machine or other support, and can be carried about by the handle 5 when disconnected from the table or other support, and that either a lamp may be supported within the ring 2 and resting upon the top 65 of the candlestick 6, or a candle may be placed in the socket in lieu of the lamp.

What is claimed is:—

1. In a device of the character described comprising a cup shaped support, supporting members connected to said cup shaped support and one of said supporting members being of greater length than the other to form a handle, a ring connected to said supporting members forming a lamp 75 bracket, a candlestick formed in said cup shaped support and extending above and below thereof adapted to receive a candle or support the base of a lamp when a lamp is being supported in the cup shaped support and means for attaching the cup shaped support to a stand.

2. In a device of the character described comprising a cup shaped support, supporting members connected to said cup shaped 85 support, a ring connected to said supporting members forming a lamp bracket, a candlestick formed in said cup shaped support and extending above and below thereof, and provided with its upper end opened 90 and its lower end closed by a solid bottom, a curved bracket connected to the candlestick adjacent the cup shaped support, said curved bracket provided with an internal screw-threaded aperture in the free end 95 thereof, a clamp screw threaded in said aperture and adapted to clamp a supporting article between the inner end of the clamp screw and the bottom of the candlestick.

In testimony whereof I affix my signature in presence of two witnesses.

EMMA J. DREVITS.
